UNITED STATES PATENT OFFICE.

ERNEST F. T. LUNDQUIST, OF CHICAGO, ILLINOIS, ASSIGNOR TO MARK R. KULTCHAR,
OF CHICAGO, ILLINOIS.

BUTTON-MAKING MACHINE.

988,478.

Specification of Letters Patent.

Patented Apr. 4, 1911.

Application filed September 18, 1909. Serial No. 518,423.

To all whom it may concern:

Be it known that I, ERNEST F. T. LUNDQUIST, a citizen of the United States of America, and a resident of Chicago, county 5 of Cook, State of Illinois, have invented certain new and useful Improvements in Button-Making Machines, of which the following is a specification.

My invention relates to button-making machines, and has for its object improvements 10 in the construction and operation of such machines.

In the accompanying drawings,—Figure 1 is an elevation; Fig. 2 is a section on line 15 2—2 of Fig. 1; and Fig. 3 is a similar section, with the lower die carrier moved to a different position.

Secured to the base 10 are two upright posts 11 and 12, on the upper end of which 20 is a head 13 vertically adjustable on the posts by nuts 14. In the center of the head 13 and midway between the posts 11 and 12 is a plunger 15, which is held in an elevated position by a spring 16 having one end bearing upon a lower portion of the head 13 and 25 an upper portion bearing against a pin 17 in the plunger 15.

Pivoted in the upwardly-extending lugs 18 is a hand lever 19 having a cam 20 30 adapted to engage the upper end of the plunger 15 and force it downward against the action of the spring 16. When the lever is elevated after such movement, the spring 16 returns the plunger 15 to its elevated position.

Secured to the lower end of the plunger 15 is a die 21, which is vertically slidable 35 upon a stem 22, which stem has a collar 23. This stem and the collar are parts of the die 40 which is secured in the lower end of the plunger 15, the part 21 being in fact a die-head, which is adapted to vertically slide upon the central portion 22.

Secured on the lower end of the plunger 45 15 just above the die is a collar 24 held in place by a set screw 25. This collar has a projection 26 extending laterally, and from this projection is a pin 27 extending downwardly parallel with the axis of the plunger 50 15 and the die 21.

Loosely mounted upon the pin 27 is an arm 28, which is held from dropping off by a dowel pin 29 in the lower end of the pin 27. The arm 28 extends laterally to engage 55 the stem 22 between the die-head 21 and the

collar 23. A spring 30 on the pin 27 normally causes the arm 28 to engage the stem 22 so as to fill the space between the die-head 21 and the collar 20, and thus prevent the die-head from sliding on the stem 22. The 60 spring 30 also permits a slight vertical movement of the arm 28 on the pin 27.

Pivoted upon the lower end of the post 12 is a quadrant-shaped arm 31 having a handle 32 by which it may be moved. Supported on the quadrant 31 are dies 33 and 34, which are adapted to be moved under the die 21 successively by moving the quadrant to either extreme of its movement, these extremes being determined by engagement of 70 lugs or projections on the quadrant with a projection 35 (see Figs. 2 and 3) on the base 10.

On one side of the quadrant 31 is an arm 36 provided with an upright pin 37, which is 75 adapted to engage the short end of the arm 28 on the pin 27. Fig. 2 shows the pin 37 removed from arm 28 and the said arm engaging the stem 22. Fig. 3 shows the quadrant thrown around to the other position so that the pin 37 strikes the projecting end of the arm 28 and moves that arm from engagement with the stem 22, and consequently from between the die 21 and the collar 23. When so removed, the die 21 can of course 80 slide on the stem. By observing Fig. 3, it will be seen that the pin 37 passes a little beyond the straight line projected through the centers of the post 12 and the pin 27. The result of this action is that the spring 30 85 does not act to push the quadrant back away from its extreme position. In other words, the passage of the pin 37 beyond the center line between 12 and 27 forms a self-locking 90 arrangement.

In operation, the dies 33 and 34 are successively moved under the die 21, and the plunger 15 is moved downward so as to force the die 21 against the horizontally-movable dies 33 and 34. When the die 33 100 is beneath the die 21, the arm 28 is between the die 21 and the collar 23, with the result that the die 21 cannot slide upon the stem 22. When, however, the die 34 is brought under the die 21, the pin 37 has pushed the 105 arm 28 away from the stem 22, with the result that upon moving the plunger 15 downward, the die 21 will slide upward on the stem 22.

The collar and screw 25 by which the 110

arm 28 is supported from the plunger 15 is made vertically adjustable by said screw 25 so as to accommodate dies of different lengths or dies having their collars 23 at 5 different distances from the lower end of the plunger 15. By having this adjustment, and by also having the arm 28 travel with the plunger 15 as it reciprocates, there is no spring tension applied in the corresponding 10 vertical movement of said arm 28.

In machines of this kind, where the plunger is moved one way by a cam and the other way by a spring, there is a certain amount of wear on the upper end of the 15 plunger 15 and on the face of the cam by which it is moved. In machines heretofore made there has been provided no means for taking up this wear. In the device herein shown, this is accomplished by means of the 20 nuts 14 adjustable on the posts 11 and 12. When there has been any considerable wear, or wear enough that requires adjustment, the head 13 may be lowered to accommodate for this wear, and in this sense the head is adjustable for this purpose.

What I claim is:

1. In a machine of the character described, a vertically reciprocating plunger and a sliding die thereon, a member for controlling the sliding action of the die, means by which said member may be adjusted, and a self locking device for holding the member from engagement with the die.

2. In a machine of the character described, a vertically reciprocating plunger, a die secured to the end of the plunger and arranged to slide thereon, and a member

for controlling the sliding action of the die, said member being secured to said plunger and being vertically adjustable with respect 40 thereto so as to adapt it to dies of different lengths.

3. In a machine of the character described, a vertically reciprocating plunger, a die carried by said plunger and movable 45 thereon, an arm secured to and vertically adjustable on said plunger near said die, a pin secured to said arm, and a member pivoted on said pin and serving to control the sliding action of said die.

4. In a machine of the character described, a vertically reciprocating and sliding die, a spring actuated member for controlling the sliding action of the die, means for adjusting said member with respect to 55 said die, and self-locking means for holding the member from engagement with the die.

5. In a machine of the character described, the combination with a reciprocating plunger and a sliding die thereon, and a 60 member for controlling the sliding action of said die, of a horizontal movable die-carrier, and a projection on said carrier arranged to move said member from operative position, said member and said projection being so 65 related to each other as to form a self-locking combination against self-displacement.

Signed at Chicago, Ill., this 13th day of September, 1909.

ERNEST. F. T. LUNDQUIST.
